UNITED STATES PATENT OFFICE.

JOHN F. PETERS, OF EDGEWOOD PARK, PENNSYLVANIA, ASSIGNEE TO WESTINGHOUSE ELECTRIC AND MANUFACTURING COMPANY, A CORPORATION OF PENNSYLVANIA.

CONNECTOR FOR REACTANCE-COILS.

1,310,588.

Specification of Letters Patent. Patented Jan. 2, 1917.

Application filed October 2, 1914. Serial No. 854,722.

To all whom it may concern:

Be it known that I, JOHN F. PETERS, a citizen of the United States, and a resident of Edgewood Park, in the county of Allegheny and State of Pennsylvania, have invented a new and useful Improvement in Connectors for Reactance-Coils, of which the following is a specification.

My invention relates to current-limiting reactance coils, and it has special reference to connectors by means of which reactance coils and the like may be electrically connected in power circuits with which they are associated.

Current-limiting reactance coils are usually connected in series with mains or power conductors which have substantially large diameters. Because of their rigidity, these mains are very difficult to handle even though their free ends are comparatively long. In installations which have been designed without due consideration being given to the proper location and method of connection for the current-limiting reactance coils, difficulty is frequently experienced in connecting the power conductors to the reactance coils unless they are provided with special connectors. For instance, it may be desirable or necessary to connect one or both ends of the power conductor to terminals at the bottom or the top of a reactance coil, or it may be more convenient to connect one end of a power conductor to a terminal at the top of the coil and the other end to a terminal at the bottom of the coil. To this end I have provided connectors for reactance coils by means of which power conductors may be connected at will either to the top or bottom of the coil or to both simultaneously.

For a better understanding of my invention, reference may be had to the following description and the accompanying drawing in which—

Figure 1 is a view, in elevation, of a portion of a current-limiting reactance coil equipped with connectors embodying my invention; and Fig. 2 is a plan view of the coil shown in Fig. 1.

Referring to the figures, the reactance coil 1 comprises a plurality of flat parallel spiral coil sections 2 which are disposed one above another, as shown. An electrical conductor 3, which comprises the spiral coil sections 2, is received in recesses formed in radial bars

or cleats 4. The superposed cleats 4 are arranged in columns and rigidly held together by means of longitudinally extending tie rods 5 which engage the inner and outer extremities of the cleats. Insulating supports 6 comprising porcelain insulators 7 and cast iron members 8, prevent the coil 1 from grounding upon the bed-plate or floor upon which it may be disposed.

In order that electrical connections may be made between the coil 1 and the power conductor in which it is inserted, I provide connectors 9 and 10. One of the free ends 11 of the conductor 3 is soldered to an apertured lug 12 which engages a conducting rod 13 near the upper portion of the coil 1. The conducting rod 13 extends longitudinally in the coil opening and projects through porcelain bushings 14 which are supported by the inwardly extending portions of a pair of superposed cleats or bars 15. The bars 15 are disposed in alignment at the top and bottom of the coil, thereby rigidly holding the conducting rod 13 in a fixed position. Recessed metallic members 16 are rigidly secured to the ends of the rod 13 which project beyond the ends of the coil. By means of the members 16, a power conductor may be electrically connected to the coil end 11 either at the top or at the bottom of the coil 1. Similarly, the coil end 17 which is disposed at the bottom of the coil 1 is connected to a rod 18 of the terminal 10. Likewise, the rod 18 is insulated from the coil 1 by means of the bushings 14. 90

From the above description, it will be understood that a power conductor may be connected to the coil end 11 either at the top or the bottom of the coil, whichever is the most convenient to do. Similarly, another conductor may be connected to the coil end 17, either at the top or at the bottom of the coil. By this arrangement, flexibility in installing the coil 1 is obtained and difficulty may be eliminated in properly securing the power mains to the coil. 110

While I have shown a single conductor comprising the coil 1, it will be understood that, when conditions warrant, it, a plurality of parallel-connected conductors may be embodied in the coil structure. In this event, the free ends of each conductor are connected to the conducting rods 13 and 18 in a manner similar to that utilized in connecting the free ends of the conductor 3. Again, it will 115

be understood that my connectors may be employed in reactance coils which are wound in the form of a plurality of concentrically disposed helices.

5 While I have herein shown and described one embodiment of my invention, it will be understood by those skilled in the art that various modifications may be made without departing from the spirit and scope of the 10 appended claims.

I claim as my invention:

1. A reactance coil comprising a pair of superposed and laterally extending members, one of which is disposed near the top 15 portion of the coil and the other of which is disposed near its bottom portion, an insulated conducting rod supported by said inwardly extending members, means for electrically connecting the rod to one terminal 20 of the coil, and terminals secured to the ends of said rod and projecting beyond the coil.

2. A reactance coil comprising superposed and inwardly extending members, an insulated conducting rod disposed in the opening 25 of the coil and supported by said members, means for electrically connecting said rod to one terminal of the coil, and terminals secured to the end portions of said rod which project beyond the coil.

3. A reactance coil comprising superposed and laterally extending members, insulating bushings secured to the ends thereof, a conducting rod supported by said members and projecting through said bushings, means for 35 electrically connecting said rod to one of the coil ends, and terminals secured to the ends of the rod which project beyond the coil.

4. A reactance coil comprising two pairs 40 of superposed and inwardly extending members, insulated bushings secured to the ends thereof, two conducting rods spaced from each other and disposed in the coil opening, each of said rods projecting through a pair of said superposed bushings, means for 45 electrically connecting the coil ends to the rods, and terminals secured to the ends of the rod which project beyond the coil.

5. A coil comprising an electrical conductor wound in the form of a plurality of convolutions, spacing members engaging the

conductor, means for holding said spacing members in rigid relationship, a longitudinally extending metallic member disposed in the coil opening, the metallic member being connected to said electrical conductor and provided at one of its extremities with an accessible terminal to which an electrical connection may be made with the coil. 55

6. A coil comprising an electrical conductor wound in the form of a plurality of convolutions, cleats engaging the conductor, means engaging the end portions of the cleats to hold them in fixed relationship to one another, an insulated longitudinally extending conducting rod disposed in the coil opening, said rod being electrically connected, at one end, to said conductor and provided, at the other end, with an accessible terminal by means of which an electrical 60 connection may be made to the coil.

7. A power-limiting reactance coil comprising a conductor wound in the form of superposed flat parallel spirals, radially extending cleats engaging the conductor and 65 spacing the convolutions thereof from one another, a longitudinally extending conducting rod disposed in the coil opening, said rod being electrically connected, at one end, to said conductor and projecting, at the 70 other end, beyond the coil to admit electrical connections to be made therewith.

8. A power-limiting reactance coil comprising an electrical conductor wound in the form of a plurality of convolutions, recessed 75 cleats adapted to receive said conductor, means for holding the cleats in rigid relationship, a pair of superposed cleats being provided with inwardly extending portions, a conducting rod disposed in the coil opening and engaging the inwardly extending portions of said pair of cleats, means for 80 electrically connecting the coil to said rod, and terminals secured to the end portions of said rod which project beyond the coil. 90

In testimony whereof, I have hereunto subscribed my name this 23rd day of Sept., 1914.

JOHN F. PETERS.
